UNITED STATES PATENT OFFICE.

THOMAS O. BENNETT, OF ATLANTIC MINE, MICHIGAN.

METAL MOLD.

SPECIFICATION forming part of Letters Patent No. 325,043, dated August 25, 1885.

Application filed February 9, 1885. (Model.)

To all whom it may concern:

Be it known that I, THOMAS O. BENNETT, of Atlantic Mine, in the county of Houghton and State of Michigan, have invented a new 5 and useful Improvement in Metal Molds, of which the following is a full, clear, and exact description.

This invention relates to sectionally-constructed metal molds for casting various articles, and is applicable to such molds of different construction and shape, according to the articles designed to be cast in them.

The invention consists of a mold with fixed 15 sectional portions having beveled lips on their inner ends, and with yielding sections or pieces arranged to form a portion of the sides of the mold and free to yield laterally and lengthwise, with their inner ends beveled to fit the beveled lips of the fixed sectional portions, 20 together with springs for forcing inward said yielding sections, substantially as hereinafter more fully set forth and claimed.

For the convenience of illustration I shall 25 here describe the invention as applied to a mold for making car-axle brasses or bearings, as such application will serve as well as any other to explain it, and, as compared with the ordinary mode of casting these brasses, said articles when made in the metal mold will be 30 free from sand, skim, and dirt, of uniform size and shape, and require no boring or finishing after they are taken from the mold, thus economizing the production of the brasses.

Reference is to be had to the accompanying 35 drawings, forming a part of this specification, in which similar letters of reference indicate corresponding parts in all the figures.

Figure 1 represents a horizontal section, on the line $x-x$ in Fig. 2, of a metal mold for casting car-brasses embodying my invention; Fig. 40 2, a vertical section of the same on the irregular line $y-y$ in Fig. 1, and Fig. 3 a side view of one of the yielding parts of one of the sections of the mold.

45 A is the bottom section of the mold, having a piece, A', which forms the core for the journal-bearing of the "brass," secured to it by bolts $b-b$, passing through the bottom of the section; or the same may be fastened in any 50 other suitable way.

The top of the mold is composed in part of

two longitudinal sections, B B, and in part of separate pieces B' B' B', forming the ends and sides of the mold. Of these the end and central body-pieces, B' B', are bolted, as at $b'-b'$, 55 or otherwise firmly secured to the sections B B, while the other pieces, B', arranged between the end pieces, B', and central body-pieces, B', and which serve to provide for the contraction of the casting in cooling, and leave spaces c 60 for the metal of the casting between them and the end pieces, B', are separate and independent sliding pieces—that is, they are free to move both laterally in direction of the length of the mold and transversely thereto—and 65 may be guided or held in place by pins p on the sides of the central body-pieces B' next adjacent to them entering oblong apertures c in the yielding sectional pieces B'. These yielding sectional pieces B' are forced inward 70 toward the center of the mold by springs s , of any suitable description, and are constructed on their inner ends with side bevels, e , which bear against correspondingly-beveled lips f 75 on the inner ends of the sides of the central body-pieces B' next adjacent to them. By means of these bevels and beveled lips $e-f$ the sectional pieces or slides B' are spread laterally by the springs s , to occupy their full space 80 in the mold before the casting is made.

After the metal has been poured in, which may be done through an end gate or hole, m , the contraction of the casting in cooling will cause the yielding pieces or slides B' to be drawn toward the central body-pieces, B', and 85 to be forced back or outward in direction of their length without fully opening or breaking the joint at their inner ends, and relieving the casting of all strain, and allowing the mold to be easily opened, the casting removed, 90 and the mold closed again readily for a succeeding casting. The action of the parts whereby the mold is relieved of such strain will be more fully apparent when the fact is taken into consideration that the metal contracts longitudinally—*i. e.*, from each end toward the center of the casting—the effect of which contraction would tend to weaken or break off the metal in the spaces c , or to cause it to bind too closely therein, but for the yielding action of the sections B'. 95

The lower section, A, and upper sections,

B B, with their attached parts B' B² B³, may be fitted together to provide for opening and closing the mold either by sliding them to their places, one on or against the other, by 5 making the upper sections with their attaching parts to lift off and clamping them, if necessary, when closed, or by hinging the upper sections, with their attached parts, as at h, to the bottom section of the mold.

10 The joints between the several sectional parts of the molds will readily provide for the escape of any gas that may form in the mold when making the casting.

Having thus described my invention, I claim 15 as new and desire to secure by Letters Patent—

1. In a sectionally-constructed metal mold for making castings, the combination, with fixed sectional portions of the mold having beveled lips on their inner ends, of yielding 20 sections or pieces arranged to form a portion

of the sides of the mold and free to slide laterally and lengthwise, with their inner ends beveled to fit the beveled lips of the fixed sectional portions, and springs for forcing inward said yielding sections, essentially as described. 25

2. In sectionally-constructed metal molds for making hollow or recessed castings, the section A, with its attached core A', in combination with the section B, the fixed end and central body portions, B' B², the latter having 30 beveled lips f on their inner ends, and the sliding and connected yielding sections or pieces B³, having bevels e, made to fit the beveled lips f, and provided with springs for forcing them inward, substantially as specified.

THOMAS O. BENNETT.
